(57) **CLAIM**

We claim the ornamental design for a clinical analyzer, as shown and described.

DESCRIPTION

FIG. 1 is a front, top and right side perspective view of a clinical analyzer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof; and,

FIG. 8 is a reference front, top and right side perspective view thereof shown in an opened position.

The broken lines in FIG. 3 are included for the purpose of illustrating portions of the clinical analyzer that form no part of the claimed design.
